CLAIM

I claim the ornamental design for a container for cotton sticks, as shown and described.

DESCRIPTION

FIG. 1 is a front perspective view of the container for cotton sticks embodying the design.

FIG. 2 is rear perspective view of a container for cotton sticks.

FIG. 3 is a plan view of the container for cotton sticks viewed from the top side of FIG. 1.

FIG. 4 is a plan view of the container for cotton sticks viewed from the front side of FIG. 1.

FIG. 5 is a plan view of the container for cotton sticks viewed from the right side of FIG. 1 where the left side is a mirror image; and,

FIG. 6 is a plan view of the container for cotton sticks viewed from the rear side of FIG. 1.
